UNITED STATES PATENT OFFICE

2,093,258

PRINTING MACHINE

Dean H. Whitehead, Chicago, Ill., assignor of
one-half to John R. Nalbach, Oak Park, Ill.

Application March 9, 1935, Serial No. 10,154

3 Claims. (Cl. 101—133)

This invention relates to improvements in printing machines.

One object of the invention is to provide a machine which is adapted for use in reproducing 5 copies of reverse masters prepared with copyable or hectograph ink, ribbons, carbon paper or the like, directly from such reverse masters or in producing copies from a hectograph surface, such as a gelatin pad; or by the use of a stencil sheet 10 or by printing directly from type, as from a stereotype plate.

A further object of the invention is to provide a printing machine having a flat bed which carries the master, whether the latter be a reverse 15 master, a hectograph surface, a stencil or a chase of type or stereotype plate, said bed being reciprocable in synchronism with a rotary drum which presses copy sheets upon the master and discharges the copy sheets into a tray.

20 A further object of the invention relates to the provision of automatic copy-sheet feeding means and sheet engaging mechanism which are synchronized with the movement of the drum whereby the sheets of a stack are successively impressed 25 upon the master sheet carried by the reciprocable bed.

Another object of the invention relates to the provision of compact means for moving the reciprocable bed carriage to initial position after 30 each printing operation.

An additional object of the invention is to provide a reciprocable bed carriage provided with means for leveling a removable bed carried thereby to insure of uniform impression of the copy 35 sheet upon the master during the printing operations.

Other objects relate to various features of construction and arrangement of parts which will be apparent from a consideration of the following 40 specification and accompanying drawings, wherein:

Figure 1 is a broken top plan view of a printing machine embodying the present improvements,

45 Figure 2 is a broken side elevation of the machine shown in Figure 1,

Figure 3 is a broken detail view of cam operated copy-sheet feeding mechanism,

Figure 4 is a horizontal sectional view taken 50 on line 4—4 of Figure 5, but showing a broken top plan of the bed,

Figure 5 is a broken end elevation of the left end machine shown in Figure 2,

55 Figure 6 is a broken vertical section taken on line 6—6 of Figure 2,

Figure 7 is an enlarged broken section taken on line 7—7 of Figure 1,

Figure 8 is a detail view of the rear end of the carriage or bed showing a clamp for securing the rear end of a master sheet in position on the bed, 5

Figure 9 is a broken side elevation of inking mechanism which is employed when type or a plate constitute the master from which copies are produced.

In the drawings 10 indicates generally the 10 frame of a machine embodying the present improvements, said frame having side members 11 and end members 12 and 13 both of which are of less height than the side members 11. The side members 11 also are provided with uprights 14 15 and 15 in which is journaled the shaft 16 carrying a sectional drum indicated generally by the numeral 17. The drum 17 is provided with end walls 18, and a semicylindrical surface 19 which presses the copy sheets into contact with the 20 master, as hereinafter described.

The side walls 11 of the frame are also provided with vertical supports 20 and 21 upon which is secured a tray support 22 which carries an inclined tray 23 upon which a stack 24 of copy 25 sheets are supported. The tray 23 is provided with vertical guides 25 and 26 for holding the sheets of paper of the stack 24 in proper alignment.

As shown in Figure 1, the guide 26 is adjustable laterally by means of slots 27 provided in the top surface of the tray 23 and held in adjusted position by means of wing nuts 28 whereby sheets of varying width can be accommodated in the machine. The tray 23 is provided with a transverse rod 29 to which are attached springs 30 which tend to slide the tray 23 to the right as viewed in Figures 1 and 2, to maintain the upper sheet of the stack 24 in contact with the feed roller 31.

The lower ends of the inclined sheets 24 rest on the plate 32 having a forward lip 33 at the rear of which is a sheet restraining hump 34.

The advancing edge of the semi-cylindrical surface 19 of the drum 17 is flat and is turned inwardly of the circumference of the drum to form a sheet engaging surface 35, shown clearly in Figure 7.

Secured on a transverse shaft 36 which is journaled in the end walls 18 of the drum is an arm 37 provided with a cam follower roller 38 which during the rotation of the drum rolls around the outer surface of the stationary cam 39 which is secured as by fastening members 40 to the 50 member 14, as shown clearly in Figure 6.

Secured to the shaft 36 interiorly of the end walls 18 of the drum is a copy sheet engaging member 41 of yoke shape and provided at its lower end with a flange 42 which may have attached to the upper surface thereof a strip of material such as rubber 43, for firmly clamping between the same and the member 35 the upper copy sheet 44 of the stack 24, which has been fed to the position shown in Figure 7, by the sheet feeding means hereinafter described.

A pair of springs 45 secured to the interior of the cylindrical surface 19 and to the arms 41a of the sheet engaging device are shown, which tend to hold the engaging member 41 in sheet engaging position. However, as the drum 17 rotates in the direction of the arrow shown in Figure 7, the follower 38 will, when it reaches the surface 39a of the cam 39, effect a counter-clockwise movement of the shaft 36 and the sheet engaging member 41 and release the copy sheet 44 as indicated by the dotted lines in Figure 7. This movement, of course, takes place during the rotation of the drum and the counter-clockwise movement mentioned is relative to the drum.

As the drum continues its rotation to move the follower 38 on to the surface 39b of the cam 39, the sheet engaging mechanism is held in inoperative position, that is, out of contact with the member 35. As the drum reaches the position shown in full lines in Figure 7, the follower 38 will pass over the inwardly directed cam surface 39c, whereupon the springs 45 will move the member 41 to the full line position. This movement, however, does not take place until another sheet has been fed into the position of sheet 44 shown in Figure 7.

The mechanism for feeding the sheets successively from the stack 24 comprises a rotatable shaft 46 provided with the feed roller 31 contacting with the upper sheet of the stack. The shaft 46 is provided with a ratchet 48 slidable axially against the tension of the spring 49 as shown in Figure 1, said ratchet 48 being non-rotatable with respect to the shaft. A mating ratchet 50 is also mounted on the shaft 46, and has secured thereto a pinion 51 meshing with which is a rack bar 52 which is pivotally secured as at 53 to the lower end of an arm 54 which in turn is pivotally mounted as at 55 to the bracket or member 15.

The arm 54 is provided with a cam follower 56 which rolls on the outer surface of a rotary cam 57 which is secured to the adjacent side wall 18 of the drum 17. Thus as the drum 17 approaches the position shown in full lines in Figure 7, the cam surface 57a will move the arm 54 clockwise as viewed in Figure 7, thereby effecting the movement of the rack 52 to the left against the action of a spring 58, and rotate the feed roller 31 in the direction of the arrow to feed the upper sheet 44 of the stack into the position shown in full lines in said figure.

As the follower 57 rides over the receding surface 57b of the cam 57 to the concentric portion 57c thereof, the spring 58 will move the rack bar 52 to the right as viewed in Figure 2, but during such movement the ratchet member 50 will click past the ratchet 48 without imparting movement to the feed roller 31. Thus the feed roller 31 operates only in one direction, that is the direction to feed the upper sheet of the stack 24 into the full line position shown in Figure 7, which movement takes place once during each revolution of the drum 17.

The drum 17 is provided with a pair of racks 75 59 provided with teeth 60 which during the print-

ing operation engage teeth 61 of the bed 62 which, as clearly shown in Figure 5, is provided with longitudinal ribs or extensions 63 which slide in grooves 64 formed in the side walls 11.

As shown in Figure 7, the racks 59 are provided with forward extensions 59a each having a single tooth 60a arranged to engage with the forward teeth 61a of the bed 62, for the purpose of initiating the sliding movement of the bed at the beginning of a printing cycle.

Thus the drum 17 in moving in the direction of the arrow from the full line position shown in Figure 7, will move the individual teeth 60a first into engagement with the teeth 61a and move the bed to the right as viewed in said figure. Before the teeth 60a and 61a are disengaged, the following teeth of the rack bars 59 will engage the teeth 61 of the bed to move the latter forwardly the full stroke thereof. By omitting the teeth between the forward teeth 60a and the remaining teeth of the rack bar, and between the teeth 61a and the remaining teeth 61 of the frame, the smoother enmeshing of the teeth 60 and 61 is effected, as will be seen.

The bed 62 in the form shown carries a removable pan-like support 65 which in turn carries the member 66 which in the form shown may be a cushioning support for the master 67. Assuming that the master for the purpose of description is a sheet typed in reverse characters in copying or hectograph ink, as in a wet process duplicating machine, the forward end of the master will be secured to the bed by a clamping bar 68 (see Figure 7).

The clamping bar 68 extends transversely of the bed and is provided with pins 69 extending through slots 70 in the bed 62 to which pins are secured springs 71 for sliding the clamping bar 68 to the left as viewed in Figure 2.

Finger pieces 72 may be provided by means of which the clamping bar 68 may be moved to the right as viewed in Figure 7, for releasing the clamping bar from the end of the master 67. The rear end of the master 67 may be held in position by means of clips 73 provided with slots 74 through which pass the wing bolts 75 which may be threaded in the rear end wall of the bed 62, as illustrated in Figure 8.

With the master thus secured in position over the cushioning member 66, the handle 76 of the machine may be turned to rotate the drum in the direction of the arrows of Figure 7, whereupon the top sheet 44 of the stack 24 will be drawn from the stack and into contact with the moistening roller 77, which is rotatably mounted in a tank 78 containing moistening liquid 79, and which is supported above the plane of the master 67 by means of suitable brackets 80.

As the drum starts its movement the forwardly projecting ends 81a of a pair of spacers 81 which are disposed between the ends of the rack bars 59 and the ends of the drum 17, initiate the rotation of the moistening roller 77 to assure that the forward portion of the lower surface of each copy sheet will be moistened. The curved surface 81b of the extensions 81a contact with the roller 77 and are of the same curvature as the cylindrical surface 19 of the drum, which surface during the continued rotation of the drum effects the rotation of the rollers 77 to continue the application of moisture to the lower surface of the sheets during their passage from the stacks into contact with the master 67.

A wiper 82 is provided in the tank 78 for wiping surplus moisture from the roller and may be

disposed between upper plate 83 and lower plate 84 which is perforated to permit absorbed moisture to drain back into the tank.

5 A screw 85 is provided for varying the tension of the wiper 82 against the roller 71.

It will thus be seen that as the top sheet 44 of the stack 24 is engaged by the member 42, it will be pressed by the cylindrical surface 19 of the drum into contact with the moist surface of the roller 71.

10 As the drum continues its rotary movement the forward teeth 60a will engage the teeth 61a of the bed and start the bed on its movement to the right as viewed in Figure 7. The following teeth 15 of the rack bar 59 will engage the teeth 61 and continue the movement of the bed during which the moistened lower surface of the copy sheet will be pressed into firm contact with the master 67. As the advancing edge of the drum approaches 20 the dotted line position shown in Figure 7, rollers 86 carried on the shaft 87 will contact with the copy sheet on the drum and will rotate in clockwise direction.

25 As the drum reaches the dotted line position of Figure 7, the sheet holding member 42 will be moved by the cam surface 39a to the sheet releasing position shown, whereupon the sheet 44 will fall away from the drum into the tray 88. Due to the contact of the rollers 86 with the 30 surface of the sheet and their rotation thereby, the sheets will be carried completely into the tray 88.

35 The tray may have an extension member 89 for accommodating sheets of different lengths. As shown in Figure 2, the shaft 87 may be held in position by means of ears 90 formed on the upper surfaces of the side members 11 of the frame.

40 As the drum continues the rotation from the dotted line position to nearly the position shown in full lines in Figure 7, the cam surface 57a will effect the actuation of the sheet feeding mechanism above described, and move the upper sheet of the stack 24 into the position of sheet 44.

45 As the member 35 of the drum reaches the full line position shown in Figure 7, the follower 38 will have moved to the position shown in full lines in said figure, and thereby permit the springs 45 to move the sheet holding member 42 into the engaging position illustrated, to thereby carry the said sheet into printing contact with the master 50 67, upon continued rotation of the drum.

55 When the rear of the rack bars 59 have disengaged themselves from the teeth 61 of the bed, the latter will be drawn to the left, as viewed in Figure 7, by means of the spring 91, which is attached at one end to the end 12 and at the opposite end to a yoke 92. The yoke is mounted on a shaft 93 which extends into opposite slides 94 disposed in slots 95 formed in brackets 96, the ends of which are bolted as at 97 to the side 60 members 11.

65 The shaft 93 is provided with a pair of sheaves 98. A second shaft 99 is journaled on the opposite end of the brackets 96 and provided with another pair of sheaves 100, (see Figure 4).

70 A flexible cable or cord 101 is attached at one end as to a yoke 102 secured to the shaft 98 and passes around the sheaves in the manner shown in said figure, and has its opposite end attached as at 103 to the lower surface of the bed 62. It will thus be seen that as the bed 62 is moved to the right by the drum due to the inter-engagement of the teeth 60a and 61a and subsequently by the teeth 60 and 61, the spring 91 will be distended, but the extent of distension will be rela-

tively short due to the arrangement of the cable and sheaves.

75 As shown in Figures 4, 5, and 6, the bed 62 is provided with openings 104 therein, within which are located eccentrics 105 which are mounted on shafts 106. Knurled wheels 107 are attached to the shafts by means of which the same can be rotated to cause the cams to elevate the member 65 as may be necessary in leveling the same, to assure of uniform contact of the copy sheet with the master during the printing operation. The shafts may be provided with ratchets 108 (see Figures 4 and 5) in engagement with which are pawls 109 which are pivoted at points 110 to the flange 111 depending from the bed 62. 15 Thus by turning either of the hand wheels 107 one side or the other of the bed can be elevated as desired, the pawls holding the leveling mechanism in adjusted position. To release the pawls 109 from engagement with the ratchets 108, another cam 112 mounted on a short shaft 113 is provided which upon being turned by means of the knurled wheel 114 will move the pawls out of engagement with the ratchets, as will be seen.

20 To facilitate the positioning of a master upon the bed, I have shown a spring pressed latch 116 located in one of the frame members 11. The bed is provided with a recess 117 into which the plunger 118 of the latch will be forced by the spring 119, when the latch is released by tilting 30 the catch 120 out of the position shown in Figure 4.

25 Thus by turning the handle 76 the bed can be moved forwardly and upon releasing the catch 121, the plunger 118 will seat in the recess 117 35 and hold the bed in the forward position against the action of spring 91. The teeth 60 of the drum, being then disengaged from the teeth 61 of the rack bars of the bed, can be turned out of position while a master is being placed in position on the bed. When the master has been fixed in position, the latch 116 may be retracted and held in such position by the catch 120.

30 By the mechanism described it will be seen that a printing machine has been provided which will 45 automatically feed sheets of paper into engaging position with reference to the rotary drum, which in turn engages and moves the master carrying bed forwardly in synchronism therewith to effect a duplication of the written or printed matter 50 carried by the master, after which the copy sheet is released from the drum and discharged into the tray 88.

55 The master 67, if desired, may be a stencil sheet held in position as above described with reference to the reverse master 67, in which case the removable cushion support 66 will be an ink saturated pad, whereby as the copy sheets are fed into contact with the master copies, stencil copies will be produced.

60 In using the device for producing the stencil copies the moistening tank 78 will not be used, although the roller 71 may be left in place to effect the smooth contacting of the copy sheets with the drum.

65 It will also be seen that the cushion member 66 may be removed, and a hectograph or gelatin pad substituted therefor, upon which pad the master is produced in reverse by the usual method. The duplication of copies will be effected in 70 the same manner as that described above.

75 If it is desired to use the mechanism for printing from type as from a stereotyped plate or the like, the plate is inserted in the bed 62 and adjusted to the proper elevation.

The moistening tank 78 in this instance will be removed by sliding the same forwardly from the machine when the drum 17 has been rotated to non-obstructing position.

5 In lieu of the moistening tank 78 an inking device illustrated in Figure 9 will be substituted. This device comprises a tank 121 holding a supply of printer's ink 122 in which is located a roller 123. A series of contacting ink transferring rollers 124 are journaled in the walls of the tank 121 as shown. The lowermost roller 125 of the series is so positioned that it contacts with the surface of the type or printing plate 126, to ink the same as the bed reciprocates.

10 15 No additional changes are otherwise required in the mechanism for making such printed copies of the master, which in this case is the plate or type carried by the bed.

20 In the description of the invention generally, and in the claims, it will be understood that the master or master sheet may comprise a paper sheet printed in reverse characters in copyable or hectograph ink, or may comprise a hectograph or gelatin pad, or a stencil, or a chase of 25 type or a printing plate. The term "printing" has been used generically as applicable to the production of copies by any of the "masters" mentioned.

30 The provision of the sheet conveyor rollers 86, which may be adjusted axially of the rod or shaft 87 to accommodate the same to sheets of different widths, is important. It will be seen that due to the contact of the cylindrical surface of the drum with the rollers 86, the copy 35 sheets continue to be conveyed forwardly into the tray 88 even after the sheet engaging means 42 has been moved to releasing position, as shown in dotted lines in Figure 7.

40 While a reciprocating bed has been specifically described as preferred, because of the various masters that can be used conveniently for different types of printing, it will be seen that a second rotary drum to carry a master may be employed in conjunction with and driven synchronously with the improved impression drum having the paper feeding and pick-up or sheet engaging and sheet releasing mechanism above described.

45 Such arrangement would have the advantage of greater speed since a suitable doctor or sheet stripper can be used with the impression drum to effect the positive removal of the printed sheets therefrom at high speed in lieu of merely releasing the sheets from the drum, as above described.

50 55 It will likewise be noted that while the sheet engaging member 42 is released to discharge the sheets with the printed faces down, the cam 39 may be so shaped that the sheets are carried around to a point substantially diametrically op-

posite the dotted line position of the releasing mechanism shown in Figure 7 to discharge the sheets into a tray with the printed sides up.

While I have shown and described the preferred embodiment of my improvements for the purpose of illustration I do not wish to be restricted specifically thereto except as so limited by the appended claims.

I claim:

1. A printing machine comprising a frame, a reciprocable master-carrying bed mounted thereon, a segmental rotary drum positioned above said bed and provided with a cylindrical surface adapted to press a copy sheet into contact with a master on said bed during the printing operation, said drum having the advancing edge directed inwardly of the peripheral arc thereof, means for synchronizing the movement of said bed in one direction with the rotary movement of said drum during said printing operation, copy-sheet engaging means carried by said drum, and provided with gripping means disposed inwardly of the drum periphery and cooperating with said edge of said drum for gripping a copy sheet fed thereto, and means for feeding a copy sheet automatically to said engaging means at a given position of rotation of said drum.

2. A printing machine comprising a reciprocable master-carrying bed, a drum rotatably positioned above said bed and having the advancing edge directed inwardly of the peripheral arc of the drum and an impression surface arranged for rolling contact with a master on said bed, means for effecting the synchronous movement of said drum and bed during the printing operation, a cam controlled sheet engaging mechanism carried by said drum and provided with sheet gripping means for securing the end of a copy sheet to said edge at a given position of rotation of said drum, and sheet feeding mechanism for feeding a sheet to said engaging means when said drum is in said position.

3. A machine of the class described comprising a member for carrying a master, a rotary segmental impression drum, a moistening roll arranged for peripheral contact with said drum and actuatable thereby, means on the drum for engaging a copy sheet and moving the same into successive contact with said roll and with said master, and arcuate means carried by said drum in advance of the impression surface thereof for initiating movement of said roll prior to contact of the same with a sheet to be moistened for effecting the moistening of the entire impression surface of the sheet prior to the contact of the same with said master.

DEAN H. WHITEHEAD.
